UNITED STATES PATENT OFFICE.

WILLIAM E. WILLIAMS, OF LONG BEACH, CALIFORNIA.

GAS FURNACE.

Application filed November 22, 1926. Serial No. 149,889.

An object of my invention is to provide a gas furnace in which a large volume of air can be quickly and effectively heated with a minimum consumption of fuel.

5 Another object is to provide a gas furnace which is simple in construction and inexpensive to manufacture.

Other objects, advantages, and features of invention may appear from the accompanying 10 drawing, the subjoined detailed description, and the appended claims.

In the drawing—

Fig. 1 is a transverse sectional view of my furnace.

15 Fig. 2 is a sectional view taken on line 2, 2, Fig. 1.

Referring more particularly to the drawing:

My furnace comprises an inner shell 1 and 20 a second shell 2 is spaced from the inner shell 1, said second shell having a plurality of outlet pipes 3 extending therefrom. An outer shell 4 is spaced from the shell 2 and is provided with an air inlet 5 through which

25 the air passing through the furnace is taken. Within the shell 1 I provide an air duct 6 which inclines upwardly at an angle and is opened at both ends thereof to the space 7 between the shells 1, 2. A second air duct 8 positioned above the duct 6 also inclines upwardly at an angle and is opened at either end thereof to the space 7.

A fuel burner 9 extends into the shell 1 below the duct 6, said burner being of any 35 suitable design and is adapted to heat the interior of the shell 1. A rearwardly inclined fire wall 10 is formed inside of the shell 1 and is positioned rearwardly of the duct 6, 8, said wall being preferably formed 40 by extending the floor of the shell upwardly so as to provide a hollow space 11 through which the incoming air passes, as will be further described.

A vertical duct 12 extends through the 45 shell 1 and is open at either end to the shell

2. A vent pipe 13 extends from the shell 1

at the rear thereof, and is adjacent the bottom of said shell, said pipe extending through the shell 2 to a suitable chimney.

In operation the burner 9 is lit and the incoming air passes through the opening 5, thence downwardly and enters the space 7; thence the air moves upwardly and enters the duct 6, and in passing through this duct it is heated by the burner 9. The air then moves 55 upwardly, enters the duct 8 where it is again subjected to heat, and then passes upwardly into the shell 2 and out of the outlets 3. The air also passes upwardly through the duct 12 and in passing there through is heated by 60 the exhaust gases, which gases are moving downwardly to the vent 13. The fire wall 10 serves to partially confine the heating in the forward end of the shell 1 and forces the hot gases to move upwardly over the top of said 65 wall as shown at 14.

Having described my invention, I claim:

1. A furnace comprising an inner shell, a second shell spaced therefrom, inclined ducts in said inner shell, said ducts being open to 70 the second shell, a burner extending into said inner shell, a fire wall in said inner shell adjacent the rear thereof, and a vent extending from said shell at the rear thereof, and a vertical duct in said inner shell back of the 75 fire wall.

2. A furnace comprising an inner shell, a second shell surrounding said inner shell and spaced therefrom, an outer shell spaced from the second shell and having an air inlet port 80 therein through which fresh air is drawn, a pair of ducts in said inner shell, said ducts being inclined upwardly at an angle and are open to the second shell, outlet pipes extending from the second shell, a rearwardly inclined fire wall adjacent the rear end of the inner shell, a vertical duct back of said fire wall and an outlet vent in the inner shell at the rear and adjacent the lower end thereof. 85

In testimony whereof I affix my signature.

WILLIAM E. WILLIAMS.
